UNITED STATES PATENT OFFICE.

WILLIAM T. HUENING, OF CHICAGO, ILLINOIS.

DISPLAY REFRIGERATOR-CASE.

1,295,507.

Specification of Letters Patent. Patented Feb. 25, 1919.

Application filed December 24, 1917. Serial No. 208,582.

To all whom it may concern:

Be it known that I, WILLIAM T. HUENING, a citizen of the United States, residing at Chicago, in the county of Cook and State of Illinois, have invented a new and useful Display Refrigerator-Case, of which the following is a specification.

The subject of this invention is a display refrigerator case intended primarily for displaying perishable articles of food, such as meat.

The main object of the invention is to provide means for producing a proper circulation of air within the case, and thereby maintain an equal low temperature throughout the case.

Another object of the invention is the provision of means for causing the air to pass directly from the freezing mixture, or refrigerant chamber, to the display compartment.

A still further object is the provision of means for controlling the flow of air.

A further object of the invention is the provision of a simple, durable, and efficient display refrigerator.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

A practical embodiment of the invention is shown in the accompanying drawings, wherein:

40 Figure 1 is a vertical longitudinal section of a display case constructed in accordance with the invention;

Fig. 2 is a cross-section on the line 2—2 of Fig. 1;

45 Fig. 3 is an enlarged detail sectional view of the air inlet port from the refrigerant chamber to the display compartment.

Referring to the drawings by numerals of reference:

50 In carrying out the invention there is provided a casing 1, of any convenient size and configuration, within which is another casing 2 which is insulated from the outer casing 1 by a dead air space, as shown, or in any other suitable manner.

The case is preferably elongated, as here-

in shown, the two ends containing the refrigerant chambers while the central portion is the display compartment proper. While the device is herein shown and described as having two refrigerating chambers, one at each end of the case, it is to be understood that the structure and the invention are not limited to two refrigerating chambers, but one or more may be used as 65 circumstances demand and permit. The display compartment has suitable transparent panels 3 which permit a complete view of the contents of the compartment, and also a slatted floor 4 which is spaced from the floor 5 of the inner casing which is inclined downwardly toward the center of the casing, as shown. The end walls 6 of the display compartment may be provided with supports for the purpose of holding a shelf 7 upon 70 which, as well as the floor 4, articles may be placed.

Secured at the central portion of the floor of the inner casing is a trap 8 from which depends an outlet pipe 9, while above the 80 trap, and extending transversely of the casing, is a housing or boxing 10 herein shown as of wire mesh but which may be formed of any suitable perforated material.

In each end of the inner casing 2 is formed 85 a refrigerant chamber the inner wall 11 of which is spaced from the end wall 6 of the display compartment. Within each refrigerant chamber a freezing mixture, such as crushed ice 12 and salt, is placed access being had to the chamber through a lid 13.

Downwardly inclined apertures 14 extend through transverse bars 14' and establish communication between the upper portion of the display compartment and the upper 95 ends of the refrigerant chambers. This permits the upper strata of warmer air in the display compartment to flow through the apertures 14 and into the upper end of the refrigerant chambers. Ducts 15 lead downwardly, beside the freezing mixture from which they are separated by the perforated wall 16 and these ducts extend to the slanting or inclined floor 17 which underlies the freezing mixture and may be separated 100 therefrom by the perforated floor 18. The floor 17 is inclined downwardly toward the floor 5, its inclination being greater than that of the floor so that water will drain along the floor 17 to the floor 5 and thence 110 to the trap 8.

As the colder air naturally seeks the lower

5 level, the air which has been cooled by the freezing mixture will move down the inclined floor 17 of the refrigerant chamber and be forced out into the space between the 10 slatted floor 4 and the floor 5. This cold air will travel between these floors, a portion escaping between the slats of the floor 4, until it reaches the central, apertured housing 10 at which place, having absorbed considerable heat, it will rise, thus establishing a complete circulation of air through the case.

15 The opening or port between the refrigerant chamber and the display compartment is preferably covered with wire gauze or the like, as indicated at 19, so as to retain the freezing mixture while allowing free egress to the air. A shutter 20 is hung transversely of the casing and is hinged or pivoted to swing vertically and may be operated to close the port or opening from the refrigerant chamber to the display compartment. Any suitable mounting may be provided for this shutter and it may be swung 25 to completely close the port when it is desired to cut off the flow of cold air from the refrigerant chamber.

30 The operation of this refrigerating display case is similar to that of most cases of the character the main difference lying in the fact that the cold air flowing from the refrigerant chambers comes directly from the refrigerating mixture and does not accumulate in a lower compartment, beneath the refrigerant chamber before entering the display compartment.

35 While to the inexperienced this may seem a small change in the structure, and one resulting in practically no advantage, still actual tests have shown that the air, after

leaving the freezing mixture, rapidly absorbs heat and, even though temporarily retained in a compartment below the freezing mixture, the temperature of the air will rapidly rise. By providing the inclined floors 17 the descending cold air passing directly from the refrigerants will be deflected inwardly to the display compartment and will not be trapped or retarded to the slightest degree.

40 Having thus described the invention, what is claimed as new and sought by Letters Patent, is:—

45 A display refrigerating case, including insulated inner and outer casings, the floor of the inner casing inclined longitudinally from each end toward the center, the pitch of the floor being greatest adjacent each end, a display compartment within the casing, a refrigerant chamber, adapted to contain the freezing mixture, at each end of the display compartment, each refrigerant chamber having an outlet port situated at the floor and communicating with the display compartment, there being communication between the upper portion of the display compartment and the refrigerant chambers, whereby air will circulate from the display compartment to the refrigerant chambers and downwardly through the freezing mixture, and directly from the freezing mixture to the lower portion of the display compartment.

50 In testimony that I claim the foregoing as my own I have hereto affixed my signature in the presence of two witnesses.

WILLIAM T. HUENING.
